UNITED STATES PATENT OFFICE.

GEORGE M. PAGE, OF HAYDENVILLE, MASSACHUSETTS, ASSIGNOR TO THE HAYDENVILLE COMPANY, OF HAYDENVILLE, MASSACHUSETTS, A CORPORATION OF NEW JERSEY.

DRINKING-FOUNTAIN.

1,276,258.

Specification of Letters Patent. Patented Aug. 20, 1918.

Application filed January 7, 1918. Serial No. 210,656.

To all whom it may concern:

Be it known that I, GEORGE M. PAGE, a citizen of the United States of America, residing at Haydenville, in the county of 5 Hampshire and State of Massachusetts, have invented a ~~new~~ and useful Drinking-Fountain, of which the following is a specification.

My invention relates to improvements in 10 drinking fountains of the type known as sanitary, and resides in a bowl and a nozzle of peculiar construction, the bowl being provided at the top with a guard, all as hereinafter set forth.

15 The objects of my invention are, first, to produce a simple, durable, comparatively inexpensive, and highly efficient fountain, of the class described, which throws a stream of water at an angle, or projects such 20 stream laterally away from the nozzle of the fountain, instead of straight upward, to the end that the drinking point is remote from the vertical plane of the discharge orifice in or the outlet of said nozzle, and 25 no water that has touched the lips of a person drinking can come into contact with said outlet; second, to provide such a fountain with means whereby the nozzle or its outlet is protected from the lips of one 30 while in the act of taking a drink; and, third, to provide a fountain of this kind that can readily be installed by connecting the same with suitable supply and waste pipes or equivalent members as usual, and 35 equipped with the customary pressure-regulating and valve-controlling means.

Other objects and advantages will appear in the course of the following description.

I attain the objects and secure the advantages of my invention by the means illustrated in the accompanying drawings, in which—

45 Figure 1 is a top plan of a sanitary drinking fountain which embodies a practical form of my invention; Fig. 2, a central, vertical section through said fountain, taken on lines 20—20, looking in the direction of the associated arrow, in Fig. 1, and, 50 Fig. 3, a similar section showing two nozzles with their appurtenances instead of one.

Similar reference characters designate similar parts throughout the several views.

This fountain consists broadly and gener-

ally of a bowl, as 1, which has a guard rail, 55 as 2, mounted thereon, and of a nozzle arranged in said bowl on the bottom thereof, at one side of the axial center of said bowl and with the axial center of said nozzle oblique to said first-named center.

The bowl 1 is designed and adapted to be 60 mounted on a supply and waste casing (not shown), which casing or the supply pipe therein is provided with the necessary or desired elements of regulation and control, of 65 usual and well-known construction. An annular flange 3, on the underside of what may be termed the base 4 of the bowl 1, is provided to fit around the top of the aforesaid casing, upon which latter said base is adapted to rest, and a central, vertical, screw-threaded opening 5, in said base, is provided for the upper terminal of the aforesaid supply pipe. A waste passage 6, in the base 4, opens at the top through the bottom of the bowl 1, and at the lower end into the space 75 within the flange 3. A passage 7 radiates from the upper end of the opening 5, and from the outer end of said passage a passage 8 extends upwardly through the bottom of the bowl 1 and through a nipple 9 which 80 rises from said bottom inside of said bowl. The axis common to the passage 8 and the nipple 9 is oblique to the axis common to the opening 5 and the bowl.

A nozzle 10 is attached to the nipple 9 by 85 means of a sleeve 11 with which said nozzle is provided or onto which it is screwed. The sleeve 11 is screwed onto the nipple 9, and said sleeve is provided within the nozzle 10 with a dome 12 in the walls of which are 90 openings or perforations 13. The upper, outlet end of the nozzle 10, above the dome 12, is constricted as usual. The base of the nozzle 10 is threaded to the upper portion of the sleeve 11 adjacent to the base of the 95 dome 12. Water entering the oblique passage 8 passes through the upper part of the sleeve 11 into the dome 12, and escapes from the latter through the openings 13 into the nozzle 10, from the upper, open end of which 100 nozzle said water is expelled or projected. The perforated dome 12 protects the interior of the supply members from foreign substances or matter that might, by accident or design, find the way or be introduced into 105 the nozzle 10; and said dome also serves as

a check on the water or a means to control the flow of the same, in addition to such other means as may be provided for that special purpose.

5 The axis of the nipple 9 is the same as that which is common to the sleeve 11 and nipple 10.

It will now be seen that the supply of water to the fountain enters at the opening 10 5 and passes through the passages 7 and 8 and the continuation of the passage 8 in the sleeve 11 and dome 12, through the openings 13, and out through the nozzle 10. It will be seen further, that, owing to the location and inclination of the nozzle 10 and supporting parts and members, the stream of water continues from the mouth of said nozzle in an oblique course, upwardly and toward the axis of the bowl 1 and beyond 15 such axis until drawn down by gravity into said bowl, the pressure of the water being regulated, by the means to which reference has been made, to insure the deflection of said stream to the necessary extent before 20 the water is projected beyond the edge of the bowl. A stream of water and its possible course are indicated by broken line at 14, in Fig. 2. The point at which the mouth is applied to the stream of water for drinking 25 purposes is, for obviously necessary reasons, and especially in view of the presence of the guard rail 2, at such a distance from the outlet of the nozzle 10 that no portion of said stream with which the lips of the person 30 drinking come in contact does or can return to the orifice whence the stream comes, that is to say, the said outlet of the nozzle. The stream 14 rises obliquely from the nozzle 10 and is projected to a point approximately 35 above the center of the bowl 1, at or a little beyond which point preferably the mouth is applied for drinking purposes. After passing 40 the aforesaid point the stream 14 describes a more or less sharp curve and falls 45 into the bowl 1 at some distance from the nozzle 10. The water in the bowl escapes through the passage 6.

The guard rail 2, which is annular, is supported from a flanged ring 15 by a plurality 50 of radial, oblique arms 16, said ring being screwed on to the rim of the bowl 1, and said rail being smaller in diameter than said rim. This annular rail, supported as it is above the bowl and being smaller than said 55 bowl at the top and of a size suitable for the purpose, prevents the head of a person from being thrust into the bowl in an endeavor to apply the lips directly to the nozzle 10, and so protects the latter from possible contamination by such means.

It is now clear that germs from the mouth can be deposited on the nozzle 10 neither by direct application of the lips to said nozzle, or indirectly by the falling back on said 60 nozzle of the water after contact with the

mouth. This fountain is, therefore, entirely sanitary in the particulars herein pointed out.

The ring 15 should be screwed on to the bowl 1 so tightly that its removal, by the person ordinarily using the fountain, is prevented; so, too, with reference to the sleeve 11 and the nozzle 10; nevertheless, all of these parts may be removed, with the aid of the proper tools, whenever occasion requires, 75 as when it is desired to clear or clean out said nozzle, or the dome 12, or both.

In the event that it shall be desired to obtain more than one stream of water from the fountain, and to have the drinking point 80 located exactly and always directly over or in line with the axial center of the bowl 1, a plurality of nozzles 10 and the appurtenances for the same may be provided, as shown in Fig. 3, wherein two nozzles and the supporting parts therefor are provided and arranged on opposite sides of said axial center. The axes of the two nozzles are inclined toward each other so that they intersect at a point directly over the center of the bowl, 90 said axes being in the same vertical plane. The streams discharged from these nozzles therefore intersect and rise as a single stream in line with the axial center of the bowl, and the drinking point is at or a little above the place of intersection. The water in descending into the bowl falls between the nozzles or between the discharge orifices of the same, provided the pressure of the two streams is properly regulated, where- 95 fore contamination of such orifices and the water escaping therefrom is prevented.

In the Fig. 3 construction the horizontal passage 7 is lengthened or extended in both directions to connect with both passages 8. 105

Any increase in the number of nozzles and their supporting parts is mere duplication and does not change the invention in any way.

More or less change in the shape, size, construction, or arrangement of some or all of the parts of the fountain, in addition to the duplication or multiplication of the discharge members, may be made without departing from the spirit of my invention. 110

I am aware that means in drinking fountains for projecting a stream or a plurality of streams horizontally or obliquely have been used before, and do not, therefore, seek to claim such means broadly.

What I claim as my invention, and desire to secure by Letters Patent, is—

1. A drinking fountain comprising a bowl having a central bottom inlet and a lateral passage therein and provided in the bottom 125 with a nipple which rises from and stands above said bottom, said nipple being located at a point remote from the center of said bowl, and communicating through said passage with said inlet, and a nozzle attached 130

to and extending above said nipple and arranged with its axis oblique to the axis of said bowl.

2. A drinking fountain comprising a bowl having a bottom inlet and a lateral passage therein and provided in the bottom with a nipple which rises from and stands above said bottom, said nipple being located at a point remote from the center of said bowl, and communicating through said passage with said inlet, a sleeve mounted on said nipple, said sleeve having a perforated dome, and a nozzle mounted on said sleeve and arranged with its axis oblique to the axis of said bowl, said sleeve and nozzle extending above said nipple.

3. A drinking fountain having a base with a central bottom inlet and a lateral passage therein, and provided in the bottom at one side of the center with a nipple which communicates with said passage, a removable sleeve mounted on said nipple, said sleeve having a perforated dome, and a nozzle

mounted on and removable from said sleeve, said nipple, sleeve and nozzle being arranged so that the axis common to such members is oblique to the axis of said bowl, and said sleeve and nozzle extending above said nipple.

4. A drinking fountain comprising a bowl having a base with inlet passages therein, and provided in the bottom at one side of the center with a nipple which communicates with said passages, a sleeve mounted on said nipple, said sleeve having a perforated dome, a nozzle mounted on said sleeve, said nipple, sleeve and nozzle being arranged so that the axis common to such members is oblique to the axis of said bowl, and a guard consisting of a ring mounted on the rim of said bowl, an annular rail, and arms between said ring and rail.
